UNITED STATES PATENT OFFICE.

BROR E. WESTLIN, OF ARLINGTON, NEW JERSEY, ASSIGNOR TO OTIS ELEVATOR COMPANY, OF JERSEY CITY, NEW JERSEY, A CORPORATION OF NEW JERSEY.

MOTOR-CAM FOR DOOR-LOCKS.

964,891.

Specification of Letters Patent. Patented July 19, 1910.

Application filed November 4, 1907. Serial No. 400,438.

To all whom it may concern:

Be it known that I, BROR E. WESTLIN, a citizen of the United States, residing at Arlington, in the county of Hudson and State of New Jersey, have invented a new and useful Improvement in Motor-Cams for Door-Locks, of which the following is a specification.

My invention relates to mechanism for controlling the operation of locks for elevator hatchway doors. In elevator systems it is customary to operate such locks by means of a cam carried by the elevator car. This cam is sometimes fixed to the car, and sometimes a motor of some form is used to retract the cam during the movement of the car, and permit the cam to be returned to operative position only when the car is brought to rest opposite a floor landing. The present invention relates to the latter form of construction in which a cam is operated by a motor mounted on the elevator car.

One of the features of the present invention resides in the improved method of mounting the motor on the elevator car, whereby the motor may be connected for operation to a cam placed on any corner or side of the car.

Another object of the invention is to provide improvements in the cam and the connections between it and the car and motor.

Other objects will appear hereinafter, the novel combinations of elements being set forth in the appended claims.

Referring to the drawings, Figure 1 is a plan view; Fig. 2 is a front elevation of a construction embodying my invention; and Fig. 3 represents a complete elevator car with my invention applied thereto.

As here shown, a motor M is swiveled by means of a pivot bolt 1 to a supporting plate 2. This plate 2 is secured to the under side of the channel beams 3 and 4 by means of a plate 5 on the upper side of the beams, and bolts 6 extending through the plates 5 and 2. The plate 5 is preferably formed with depending flanges 7 which engage the inner sides of the channel beams and help to retain the parts securely in position. The lower plate 2 may also be provided with similar flanges extending upwardly between

the beams. The beams 3 and 4 are the overhead cross-beams forming part of the framework of the car, and to which is attached the hoisting rope or cable.

The car 8 carries a cam device C which in the present instance is located at one corner of the car. This cam device comprises a plate 10 secured to the outer surface of the car, two parallel rock-arms 11, 11, pivoted at 12, 12, to the plate 10, and a cam 9 carried by the arms 11, 11, and to which they are pivotally connected at 13. The cam 9 is limited in its downward movement by a stop 14 in the path of an arm 11. A flexible connection 15, such as a cord or chain, having one end attached at 16 to the cam 9, extends over a direction sheave 17 on the plate 10, from thence upwardly and over a sheave 18 on the car, and to the sheave 19 to which the other end of said connection is fastened. The sheave 19 is connected to the motor shaft to rotate therewith. When the motor is operated to wind a portion of the cord 15 on the pulley 19 the cam 9 will be moved upwardly and inwardly to an inoperative position.

It will be noted that the point 16 at which the cord 15 is connected to the cam is so located with respect to the direction sheave 17 that the pull on the cord will tend to move the cam upwardly until the arms 11 are nearly vertical. When the motor pull on the cord is released, the cam 9 will move downwardly, owing to its own weight, aided by the coil spring 20 connected at its opposite ends to the cam 9 at 26 and plate 10 at 27, respectively.

A compression spring 21 through which the cord 15 extends bears at its lower end against a stop 22 secured to the cord and at its upper end against the sheave frame 18 through which the cord passes. When the motor is energized to wind the cord and move the cam 9 upwardly, the spring 21 is compressed, but when the motor is deenergized the pressure of the spring is sufficient to rotate the motor armature back to initial or normal position, at the same time lowering the stop 22 so that the cam 9 will be free to move downwardly as before described.

An important feature of the present invention is the way in which the motor is mounted, as already described, and which

permits of its adjustment so that it may be used with a cam located at any corner or at any point along the sides of the car. Being swiveled, it may be rotated to bring its pulley in line with any point along the front edge 25 of the car, or the side edges. If the cam is located on the opposite side of the car, the plate 2 may readily be reversed so as to project beyond the beam 4, thus placing the motor on the same side of the cross-beams as the cam. The plates 2 and 5 may also be adjusted to any desired position longitudinally of the beams 3, 4.

In operation the motor M may be energized when current is supplied to the main motor which operates the elevator car, and deenergized when the current is cut from the main motor to bring the car to rest opposite a floor landing. The cam is therefore held in its inoperative or non-engaging position as the car moves past the several hatchway doors, and is only moved outwardly to operative or engaging position to unlock a door when the car is stopped opposite said door. It should be understood that any method of control for the operation of the motor M may be used, and as this forms no part of the present invention a controlling system has not been illustrated here.

Obviously various changes in the detail of construction and arrangement of parts might be made by those skilled in the art without departing from the spirit and scope of my invention, and I desire therefore not to be limited to the exact construction disclosed.

What I claim as new and desire to have protected by Letters Patent of the United States is:—

- 40 1. In elevator door lock apparatus, the combination with a motor mounted in fixed position, of a motor pulley, a cam, and a flexible connection between the cam and pulley.
- 45 2. In elevator door lock apparatus, the combination with an elevator car, of a motor pulley mounted on the elevator car, a support secured to the car, parallel arms pivoted to the support, a cam pivoted to the arms, a direction sheave carried by said support, and a flexible member connected to the cam, passing over said sheave, and connected to the motor pulley.
- 50 3. The combination with a motor, of a cam, and a flexible operating connection between the motor and cam permitting a return of the motor after operation independently of the return of the cam to its initial position.
- 55 4. The combination with a motor and a cam, of a flexible operating connection therebetween, a device for returning the motor to initial position, and means for returning the cam to initial position after operation.

5. The combination with a motor and a cam, of an operating cord connected to the motor and cam, and a spring connected to the cord and operative to return the motor to initial position after operation.

70

6. The combination with a motor and a cam, of an operating cord connected to the motor and cam, a spring connected to the cord and operative to return the motor to initial position after operation, and means independent of said spring for returning the cam to initial position.

75

7. The combination with a motor pulley and a cam, of a cord or rope connected at its ends to the cam and motor pulley, respectively, a coil spring surrounding the cord, a stop on the cord for one end of the spring, and a stationary stop for the other end of the spring, said stops being positioned to cause a compression of the spring when the motor is operated.

80

8. The combination with a support, of parallel arms pivoted to the support, a cam carried by the arms, a direction sheave pivoted to the support between the arms, a cord connected to the cam and extending diagonally to the sheave, and means connected to the cord for operating the cam.

85

9. The combination with a support, of a pair of parallel arms, each pivoted at one end to the support, a cam pivotally connected to the opposite ends of said arms, a direction sheave journaled on the support between the arms, a cord connected to the cam and engaging the direction sheave, and means connected to the cord for operating the cam.

95

10. The combination with a support, of a pair of parallel arms pivoted to the support and normally extending outwardly therefrom in a horizontal direction, a vertical cam pivoted to the outer ends of the arms, a direction sheave on the support and between the arms, a cord connected to the cam and extending inwardly and upwardly to the sheave, and means connected to the cord for operating the cam.

105

11. The combination with a vertical support, of parallel arms extending outwardly from the support and pivoted at their inner ends on horizontal pivots at the opposite ends of the support, a cam pivotally connected to the outer ends of the arms, a direction sheave journaled to the support substantially in line with said pivots, a cord engaging said sheave and extending diagonally downwardly and outwardly therefrom and connected to the cam, means connected to the cord for moving the cam upwardly and inwardly, and a stop to limit the downward movement of the cam.

115

12. In elevator door locking apparatus, the combination with a car, of a motor swiveled on the frame of the car, a cam, and

120

125

operating connections between the motor and cam.

13. In elevator door lock apparatus, the combination with a car, of a motor mounted on the car and adjustable thereon about a vertical axis, a cam, and operating connections between the motor and cam.

14. In elevator door lock apparatus, the combination with a car, of a motor mounted on the car, said motor comprising a horizontal shaft and a drive pulley thereon, a direction sheave secured to the car, said motor being adjustable to bring its drive pulley in line with the direction sheave, a cam inovably mounted on the car below said sheave, and a cord or rope connected to the cam and to the motor pulley and passing over said sheave.

15. In an elevator, the combination with a car, of a car frame comprising horizontal overhead beams, a plate secured to and extending beyond the beams, a motor mounted on the extending portion of the plate, cam mechanism carried by the car below the motor, and a flexible connection between the motor and said mechanism.

16. In an elevator, the combination with a car frame comprising horizontal beams, of a plate secured to the under side of said beams and having a portion projecting beyond the beams, and a motor mounted on said projecting portion.

17. In an elevator, the combination with a car frame, comprising overhead beams parallel to the edge of the car, of a plate extending across the beams and secured there-

to, said plate comprising flanges engaging the beams, and a motor mounted on the plate.

18. In an elevator, the combination with a car frame comprising parallel overhead beams with their under surfaces in the same horizontal plane, a plate extending across the beams, means for clamping the plate against said under surfaces, said plate comprising flanges engaging the lateral surfaces of the beams, and a motor mounted on the plate.

19. In an elevator, the combination with a car frame comprising parallel overhead beams, of plates located respectively above and below the beams, bolts extending through the plates and securing them in position against the beams, the lower plate having one end extended beyond the beams, and a motor mounted upon said extended end.

20. In an elevator, the combination with a car frame comprising parallel overhead beams, of a plate bolted to the under surface of the beams and having one end extended beyond the beams, and a motor mounted on said extended portion and adjustable about a vertical axis.

In testimony whereof, I have signed my name to this specification in the presence of two subscribing witnesses.

BROR E. WESTLIN.
